[57] ABSTRACT

A machine is disclosed for coating agricultural produce with liquid. The machine comprises a frame, an applicator mounted to the frame for rotation about an axis, applicator drive means for rotating the applicator, and produce guide means for guiding produce into contact with the applicator. A reservoir is mounted to the frame and adapted to be filled to a preselected level with liquid. The reservoir includes a wall rising above the preselected level from beneath the preselected level and defining at least one port elevated above the preselected level and the applicator. Sweeping means are mounted for movement within the reservoir. Sweep drive means are provided for moving the sweeper means over the wall from beneath the preselected level above the preselected level adjacent the port. Liquid guide means are also provided for guiding liquid passing through the port onto the applicator.

FIG A

FIG 2**FIG 3**

PRODUCE COATING MACHINE HAVING VISCOUS LIQUID DISPENSING MEANS

BACKGROUND OF THE INVENTION

This invention relates generally to coating machines, and more particularly to agricultural produce coating machines of the type which employ viscous liquid dispensing means.

Produce coating machines have heretofore employed means for dispensing viscous liquids such as waxes onto brush-type applicators which in turn apply the wax to produce brought into brushing engagement therewith. These dispensers have included relatively small nozzles the size of which, in combination with the pressure of the wax, has established the relatively low rates at which the wax is dispensed.

Though the just described viscous liquid dispensers have worked well in applying liquids consisting essentially of homogeneous solutions of waxes, they have failed to operate satisfactorily when certain other liquids and particles have been added to the wax to be applied simultaneously therewith. For example, various fungicides have recently been added to the wax solutions which have tended to clog the small nozzles which have, as previously stated, been quite small in order to limit the rate of wax application. In addition, where the rate at which produce is being processed through the coating machines have been small, and likewise the rates at which the wax and fungicide mixtures have been fed through the nozzle of the dispenser have been small, the fungicides have tended to settle before passing through the nozzles and onto the produce.

Accordingly, it is a general object of the present invention to provide an improved produce coating machine.

More specifically, it is an object of the present invention to provide an improved agricultural produce coating machine of the type having viscous liquid dispensing means.

Another object of the invention is to provide an agricultural produce coating machine with improved means for dispensing viscous liquids at relatively low rates.

Another object of the invention is to provide a device for dispensing viscous liquids at low rates which device does not tend to clog nor require frequent cleansing operations.

Another object of the invention is to provide an agricultural produce coating machine which employs a dispenser for dispensing mixtures of wax and fungicide, and which includes means for continuously stirring the mixtures to inhibit settling of the fungicide from the wax.

Yet another object of the invention is to provide a device for dispensing viscous liquids at low rates of relatively simple and economic construction.

SUMMARY OF THE INVENTION

In one form of the invention a machine is provided for coating agricultural produce with liquid and comprising a frame and an applicator mounted to the frame for rotation about an axis. Applicator drive means are provided for rotating the applicator and produce guide means for guiding produce into contact with the applicator. A reservoir is mounted to the frame and adapted to be filled to a preselected level with liquid and with the reservoir having a wall rising above the preselected

level from beneath the preselected level and defining at least one port elevated above the preselected level and the applicator. Sweeping means are movably mounted within the reservoir. Sweep drive means are provided for moving the sweeper means over the wall from beneath the preselected level above the preselected level adjacent the port. Liquid guide means are provided for guiding liquid passing through the port onto the applicator.

10 In another form of the invention a device is provided for dispensing viscous liquids at low rates. The device comprises a tubular reservoir adapted to be filled to a preselected level with viscous liquid and having dispensing port means disposed above the preselected level. A rotatable shaft is mounted centrally within the tubular reservoir and means provided for rotating the shaft. A set of axially spaced brushes is mounted on the shaft in sweeping engagement with the tubular reservoir to sweep liquid above the preselected level and into the dispensing port means.

BRIEF DESCRIPTION OF THE DRAWING

FIG. 1 is a perspective view of an agricultural produce coating machine embodying principles of the invention in a preferred form.

FIG. 2 is a side view in elevation of a portion of the machine shown in FIG. 1 with a side panel removed.

FIG. 3 is a perspective view of dispensing device incorporated into the produce machine shown in FIGS. 1 and 2 with a portion of the device cut away to reveal interior components thereof.

DETAILED DESCRIPTION OF THE DRAWING

Referring now in more detail to the drawing, there is shown in FIGS. 1 and 2 an agricultural produce coating machine 10 having a frame 12 defining a chamber 14 in which are mounted two shafts 15 and 16 about which two cylindrical horse hair brushes 17 and 18 are respectively secured. Beneath brushes 17 and 18 are rotatably mounted a set of six relatively small brushes 20 for rotation about parallel shafts 21. An input chute 23 is provided to guide produce between the two relatively large brushes 17 and 18 and the relatively small brushes 20. A discharge chute 25 is provided to receive the produce after having passed through the chamber.

An electric motor 27 is provided for driving brushes 17 and 18 in clockwise directions, and brushes 20 in counterclockwise directions, as viewed in FIG. 2, so as to continuously urge the produce through chamber 14.

50 An agitation tank 30 is provided having a pump 32 mounted thereatop to affect agitation of liquid disposed within the tank and to pump the liquid up and into the tubular reservoir 35 through an intake conduit 36. As may be seen most clearly by reference to FIG. 3, return pipe 38 extends downwardly from within reservoir 35 and back through a flexible conduit to the agitation tank. This top lip 39 of the return pipe is disposed along a preselected plane within the reservoir to establish the surface level of liquid housed within.

With continued reference to FIG. 3 a tubular reservoir 35 is seen to include a set of axially spaced apertures or ports 40 extending through the walls of the reservoir above the level established by lip 39 of return pipe 38. Just beneath ports 40 is mounted a drip board or baffle 41 to guide liquid exiting ports 40 onto brush 18 as shown in FIG. 2. Two pillar blocks 43 are rigidly mounted adjacent the opposite ends of reservoir 35 which pillar blocks have sleeve bearings 44 therein in

which is rotatably journaled a shaft 45 which extends between blocks along the axis of the tubular reservoir. A sprocket 47 is secured to the shaft to be driven by a chain housed within chain guard 49 coupling the sprocket with another electric motor 51. If desired, only a single electric motor may be used to drive both the brushes within chamber 14 as well as shaft 45 within reservoir 35. However, inasmuch as it is often desirable to regulate the speed of the shaft 45 independently of that of the brushes within chamber 14 two electric motors are preferably used with independence speed adjustment capability.

With continued reference to FIG. 3, a set of brushes 50 is seen to be mounted to shaft 45 by means of a mounting plate 52 which is welded to one side of shaft 45 and another mounting plate 53 by bolts 55 to the other mounting plate with brushes 50 sandwiched therebetween and with an edge of mounting plate 53 resting upon shaft 45. The ends of the brushes distal shaft 45 are in brushing engagement with the inner surface of the tubular reservoir 35. They may be axially located to pass either over or between ports 40.

In operation, the brushes disposed within chamber 14 are rotated by coupling motor 27 to a source of electric current, and the brushes disposed within the dispensing device rotated by coupling motor 51 also with a source of electric current. With all of the brushes then rotating agricultural produce such as a cucumbers, peaches, peppers, plums, nectarines and tomatoes are introduced into input chute 23 where they gravitate into contact with brushes 18 and 20. From here the rotating brushes urge the produce through chamber 14 atop brushes 20 and beneath brushes 18 and 17 and then out into discharge chute 25 where they may be collected. During this process brushes 15 within reservoir 35 are slowly rotated whereby the ends of brushes 50 pass beneath the surface of liquid 59 disposed within the reservoir and then emerge urging liquid up along the inner surface of the reservoir and over ports 40 from which the liquid emerges from the reservoir and onto drip plate 41. From the drip plate drops of the liquid fall steadily onto brush 18 at a relatively slow rate as depicted in FIG. 2. From brush 18 the liquid is coated onto the produce and also onto the brush 17 which, at point of contact, is rotating in an opposite direction of brush 18. From brush 17 an additional portion of the liquid is coated onto the produce. The slow revolution of shaft 45 and brushes 50 within reservoir 35 continuously urges liquid above the level established by the top of overflow pipe 38, through ports 40, and then onto brushes 18 and 17.

The continuous motion of the brushes within the dispensing device also serves to agitate the liquid to prevent settling of the heavier elements of the mixture from occurring. Simultaneously, pump 32 agitates the mixture within tank 30 while continuously circulating the liquid through the tank and dispensing device. In this manner the quantity of liquid flowing through the dispensing device is substantially greater than that being dispensed to brushes 17 and 18 which further inhibit settling and clogging.

It should be understood that the just described embodiments merely illustrate principles of the invention in preferred forms. Many modifications may, of course, be made to the specifically illustrated embodiments without departure from the spirit and scope of the invention as set forth in the following claims.

What is claimed is:

1. A machine for coating agricultural produce with a liquid and comprising a frame; an applicator mounted to said frame for rotation about an axis; applicator drive means for rotating said applicator about said axis; produce guide means for guiding produce into contact with said applicator; a reservoir mounted to said frame and adapted to be filled to a preselected level with liquid and with said reservoir having a wall rising above said preselected level and defining at least one port elevated above said preselected level and said applicator; sweeping means mounted for movement within said reservoir; sweep drive means for moving said sweeper means over said wall from beneath said preselected level to above said preselected level adjacent said port for lifting only a portion of said liquid along said wall and for urging the same out of said port; and liquid guide means for guiding liquid passing through said port onto said applicator, the contour of said wall being such that said sweep means will urge the liquid along said wall and through said port to emerge as liquid which adheres to said wall and is received on said liquid guide means and will thereafter drip therefrom onto said applicator.
2. A machine in accordance with claim 1 wherein said reservoir comprises a cylindrical tube providing said wall with a uniform curvature adjacent said port and over which said sweep means travels and wherein said sweep drive means includes a shaft mounted for rotation within said cylindrical tube.
3. A machine in accordance with claim 2 wherein said shaft is mounted along the axis of said cylindrical tube and wherein said sweeping means includes at least one brush mounted to said shaft for engaging said wall at a substantially uniform distance from said shaft as said brush moves out of said liquid and past said port.
4. A machine in accordance with claim 1 wherein said applicator comprises a horse hair brush.
5. A machine in accordance with claim 1 further comprising a liquid agitation tank in fluid communication with said reservoir and means for circulating said liquid from said tank to said reservoir and back to said tank for maintaining said level of said liquid in said reservoir.
6. A device for dispersing viscous liquids at low rates and comprising a tubular reservoir adapted to be filled to a preselected level with a viscous liquid and having dispersing port means disposed above said preselected level; a rotatable shaft mounted centrally within said tubular reservoir; means for rotating said shaft; a set of axially spaced brushes mounted on said shaft in sweeping engagement with said tubular reservoir to sweep liquid above said preselected level and into said dispersing port means; and a liquid run off plate mounted adjacent to the outer surface of said reservoir below said dispersing port means for receiving the liquid emerging from said dispersing port means and for directing the liquid by gravity therefrom.
7. A dispersing device in accordance with claim 6 wherein said dispersing port means comprises a set of axially spaced ports extending through said tubular reservoir above said preselected level.
8. A dispensing device in accordance with claim 7 wherein said liquid run-off plate is mounted to an exterior surface of said tubular reservoir immediately beneath said set of axially spaced ports.
9. A dispensing device in accordance with claim 8 in combination with viscous liquid application means mounted for rotation below said liquid run-off plate.

10. A device for dispensing viscous liquids at low rates and comprising a tubular reservoir adapted to be filled to a preselected level with a viscous liquid and having dispensing port means disposed above said preselected level; a rotatable shaft mounted centrally within said tubular reservoir; means for rotating said shaft; and a set of axially spaced brushes mounted on said shaft in sweeping engagement with said tubular reservoir to sweep liquid above said preselected level and

5 into said dispensing port means, said set of brushes being mounted to said shaft by means of a first mounting plate welded to one side of said shaft and a second mounting plate secured to said first mounting plate in abutment with a side of said shaft diametrically opposed said one side and with ends of said brushes sandwiched between said first and second mounting plates.
